US0D1083830S

(12) **United States Design Patent** (10) **Patent No.:** **US D1,083,830 S**
(45) **Date of Patent:** **** Jul. 15, 2025**

(54) **ENERGY STORAGE CHARGER**

(71) Applicant: **Positec Power Tools (Suzhou) Co., Ltd.**, Suzhou (CN)

(72) Inventors: **Wang Huo**, Jiangsu (CN); **Fanqing Ding**, Jiangsu (CN)

(**) Term: **15 Years**

(21) Appl. No.: **35/520,164**

(22) Filed: **Feb. 28, 2023**

(80) **Hague Agreement Data**

Int. Filing Date: **Feb. 28, 2023**

Int. Reg. No.: **DM/228296**

Int. Reg. Date: **Feb. 28, 2023**

Int. Reg. Pub. Date: **Mar. 1, 2024**

(57) **CLAIM**

The ornamental design for an energy storage charger as shown and described.

DESCRIPTION

1. Energy storage charger

1.1: Perspective

1.2: Front

1.3: Back

1.4: Left

1.5: Right

1.6: Top

1.7: Bottom

Title of the design: Energy storage charger; The energy storage charger is used for storing electrical energy and charging; Design 1 claim the overall shape of the design; The most representative drawing or photograph is the perspective view of design 1; Design 1 is deemed as the base design.

Features shown in broken lines form no part of the claimed design.

1 Claim, 7 Drawing Sheets
